UNITED STATES PATENT OFFICE.

HILLARD A. ARONSON, OF TOWER, MINNESOTA, ASSIGNOR OF ONE-HALF TO JOSEPH A. QUINN, OF TOWER, MINNESOTA.

ROW-LOCK.

1,293,298.

Specification of Letters Patent. Patented Feb. 4, 1919.

Application filed June 12, 1917. Serial No. 174,291.

To all whom it may concern:

Be it known that I, HILLARD A. ARONSON, a citizen of the United States, residing at Tower, in the county of St. Louis and State 5 of Minnesota, have invented certain new and useful Improvements in Row-Locks; and I do hereby declare the following to be a full, clear, and exact description of the invention, such as will enable others skilled in the art 10 to which it appertains to make and use the same.

This invention relates to improvements in row locks for row boats.

The object of this invention is to provide 15 a row lock in which the oar may work without noise or wear either upon the oar or row lock and it consists in forming the horns of suitable metal having their inner surfaces provided with a groove, the ends of which 20 terminate into a recess and a pad of rubber or other suitable flexible material of the configuration of the interior of the horns removably fitted in the groove and has its ends inserted up into the recesses, thus the ends 25 of the pad are prevented from being worn during the placing in or taking out of the oar from the oar lock.

A further object of this invention is to 30 provide the horns with the groove which terminates into the recesses in the upper ends of the horns, this permitting the ends of the rubber pad or the like to be arranged in the recesses and any fear of the pad being accidentally displaced from the groove of the 35 horns obviated.

A still further object of this invention is to 40 provide the horns with the groove which terminates into the recesses adjacent the upper ends of the horns and the ends of the rubber pad or the like inserted in these recesses and fitted in the groove thus obviating the necessity of other retaining means thereby providing a noiseless row lock and one in 45 which the rubber pad or the like has its ends protected during the raising and placing of the oar in the oar lock and between the horns.

A further object of the invention is to provide the horns of the lock with a removable noiseless resilient pad, which will prevent 50 the oars from sliding into the water.

A still further object of this invention is to provide a row lock of this character which will be simple, practical and comparatively inexpensive in construction and one that can 55 be manufactured and sold at a low cost.

With these and other objects in view the invention consists in the novel combination and arrangement of parts hereinafter more fully described and set forth in the claim hereto appended.

60

In the drawing—

Figure 1 is a front elevation partly in section illustrating the oar lock made in accordance with this invention,

Fig. 2 is a vertical sectional view of the 65 same, and

Fig. 3 is a horizontal transverse sectional view taken through the horns of the oar lock.

Like numerals of reference designate corresponding parts in all the figures of the drawing.

Referring to the drawing, the numerals 1 and 2 represent the horns of the lock formed of any suitable metal and they are provided with the annular retaining disk 3 which has formed on and depending from the under side face the vertical shank 4, which shank is concentrically related to the disk 3 and is adapted to be removably arranged in the socket formed in the gunwale of a boat to permit the oar locks to be removably fitted thereto.

The inner surface of the horns is provided with a substantially semi-circular 85 groove 5 which extends throughout approximately two-thirds of the entire length of the horns 1 and 2 and have their ends terminating into retaining recesses or sockets 6 adjacent the upper ends of the horns 1 and 2 as 90 illustrated in Fig. 1. The upper ends of the horns 1 and 2 are flared outwardly as at 7 to facilitate the guiding of the oar into and between the horns when in use. The ends of the groove terminate up into the ends of the 95 horns 1 and 2 thus forming recesses 6, the purpose of which will be hereinafter more fully described.

A rubber pad 8 constructed of any suitable material such as rubber or the like is substantially cylindrical in cross section and arranged in the groove 5 and has its ends extending up into the recesses 6 formed in the adjacent ends of each of the horns 1 and 2 thereby the ends of the pad 8 will be protected and prevented from being worn or struck when placing an oar between the horns or taking the same therefrom, thereby preventing accidental derangement of the pad 8 in the groove 5 when the device is in use.

100

105

110

It is to be understood that the pad 8 provides a noiseless oar lock and prevents wear upon the horns thereof and the recesses in which the ends of the pad fit prevent the oar from wearing the ends of the pad and causing the same to be displaced therefrom during the operation of placing the oar in or taking it from between the horns.

What is claimed is:

- 10 An oar lock comprising a shank, a retaining disk formed at the upper end of the shank, a pair of horns formed integrally with the upper side of the disk centrally thereof, the inner edges of the horns pro-

vided with a longitudinal groove extending 15 throughout the greater length thereof and terminating at its ends in retaining sockets, and a resilient pad of circular form in cross section arranged in said groove with its ends extending into said retaining sockets, for the 20 purpose specified.

In testimony whereof I affix my signature in presence of two witnesses.

HILLARD A. ARONSON.
